UNITED STATES PATENT OFFICE.

CHARLES C. MEUTSCH, OF CHICAGO, ILLINOIS.

MATTRESS AND UPHOLSTERING CONSTRUCTION.

1,333,031.

Specification of Letters Patent.

Patented Mar. 9, 1920.

Application filed May 25, 1916. Serial No. 99,719.

To all whom it may concern:

Be it known that I, CHARLES C. MEUTSCH, a citizen of the United States, and resident of Chicago, in the county of Cook and State 5 of Illinois, have invented certain new and useful Improvements in Mattresses and Upholstering Constructions, of which the following is a full, clear, and exact specification.

- 10 This invention relates to improvements in mattresses and upholstering constructions of the "double deck" type in which heretofore a series of convolute springs comprising a set are supported by crossed straps of burlap secured at their ends to the bottom edges of a wooden frame above which the springs project, and are anchored to the top edges of the frame and also connected together by a twine of sufficient length for 15 such purposes, and these springs in turn support another set of springs similar thereto likewise connected with each other, and anchored to the wooden frame by means of a twine string.
- 20 25 The prime object of my invention broadly stated is to provide mattress and upholstering constructions with a fabric cover for the bottom ends of a series of coiled springs so constructed as to provide a successful means 30 for bodily suspending the mattress in its operative position in a frame, and which when used in a double deck spring structure provides a cover for the top of the bottom set of springs, and a means for successfully 35 anchoring both sets of springs to their surrounding frames in the absence of a twine anchorage.

- 40 A further object of my invention is to provide a simple and effective means for stiffening the surrounding edges of the upper spring structure of a double deck mattress and upholstering construction, and by which the stiffening wire therefor may be conveniently inserted and removed from 45 the cover.

- With these ends in view, my invention finds embodiment in certain features of novelty in the construction, combination and arrangement of parts by which the said objects and certain other objects are attained, all as hereinafter fully described with reference to the accompanying drawings, and more particularly pointed out in the claim.

In said drawing:

Figure 1 illustrates a top plan view of a 55 mattress and upholstering construction in which my invention finds embodiment.

Fig. 2 is a transverse vertical section thereof on the line 2—2 of Fig. 1, illustrating in dotted lines the adaptation thereof 60 to a double deck structure, and—

Fig. 3 is a fragmentary detail illustrating the use and location of twines for securing the reinforcing wires to the cover and the end coils of the springs adjacent thereto. 65

Similar characters of reference indicate the same parts in the several figures of the drawing.

4 indicates a series of upright coiled springs inclosed in individual pockets 5 of 70 any construction suitable therefor, but preferably formed by strips of textile fabric crossing each other stitched at their ends respectively to the top surface 6 and bottom surface 7 of a cover of textile fabric extending over the ends of the pockets and 75 springs, as shown and described in my pending application.

Surrounding the spring containing pockets are side pieces 8 of textile fabric which 80 may be stitched to the top surface of the cover, or be integrally formed therewith as desired.

The bottom surface of the cover, however, is provided with outwardly projecting extensions 9—9 at both its sides and ends, 85 which are preferably formed integrally with the bottom surface of the cover, but may be from separate strips secured thereto as indicated at 11 in Fig. 2. 90

These projecting side strips or extensions 9 provide a means for suspending the mattress in a frame 12, which for example, may constitute the side and end bars of either a bed, a cot or an upholstering back 95 or seat frame, as illustrated in Fig. 1.

For a double deck mattress and for upholstering purposes, the extensions 9 are particularly adapted as a means for anchoring the upper or outer spring construction 100 to the frame 13 and upper or inner seat of springs 14 indicated by dotted lines in Fig. 2, seated upon the burlap strips 15, for the reason that such extensions not only dispense with anchoring cords heretofore required, and exclude dust from the bottom or inner spring structure, but furnish a 105 stronger and more durable anchorage than,

and which is just as flexible as are anchoring twines, while in the meantime the bottom surface of the cover for the upper or outer set of springs provides a covering for 5 the upper ends of the inner springs 14.

It is also proper to observe that for the connection of twine strings with the outer set of springs, and anchoring them to the frame substantially more time and skill is 10 required than for anchoring to the frame extensions already and before necessarily connected with such springs, and that furthermore as one or more of the anchor strings frequently break from the strains they are 15 exposed to, this objection is removed by the extension of the bottom surface of the outer springs as herein shown and described.

As a means for reinforcing the surrounding edges of the outer spring structure 20 when used for upholstering purposes, my invention includes the use of a fold 16 in the covering converted into a hollow tube by means of a line of stitching 17 in which to project a rod 18, the diameter of which is 25 such as to fit and be somewhat closely confined by the fabric tubing.

The rod 18 may be continuous from end to end, but for convenience of insertion is 30 preferably constructed in two sections, the free ends of which meet, and preferably overlap each other at the center of either the sides or end edges of the cover, and in either event are connected and secured to the adjacent top coils of the springs by a 35 stitching twine 19 as clearly illustrated in Fig. 1, and which may be done by means of a sacking or other needle.

In this connection it should be observed 40 that the lines of twine stitching 20 and 21 are the means by which to connect together

the opposing end coils of springs adjacent each other.

In the construction of double deck structures containing my invention, the bottom sets of springs have their end coils connected with the lower coil and are anchored to the side bar 13 by means of twine, as indicated at 22, 23, and 24 by dotted lines, the disuse of which for the upper set of springs is provided for by my invention, as 50 before described, but it will be no departure from my invention to connect the end coils of the upper springs & with the lower coils thereof by means of twine, if for any reason it may be desirable or necessary to do so. 55

Having described my invention, what I claim and desire to secure by Letters Patent is:

A device for the purpose described comprising in combination a frame, a series of 60 coiled springs supported from and projecting outwardly beyond said frame, means for connecting said springs with the top edges of said frame, another series of coiled springs, a fabric covering inclosing said 65 springs, the second set of coiled springs being supported endwise upon said first mentioned coiled springs, a covering surrounding and inclosing the supported springs, the bottom surface of which is provided with 70 extensions adapted to connect the inclosed spring structure with and anchor it to the top edges of said surrounding frame.

In witness whereof, I have hereunto set my hand and affixed my seal, this 22nd day 75 of May, A. D. 1916.

CHARLES C. MEUTSCH. [L. S.]
